UNITED STATES PATENT OFFICE.

WILLIAM J. REGAN, OF WILKINSBURG, AND ENOCH GEORGE, JR., OF PITTSBURGH, PENNSYLVANIA, ASSIGNORS TO THE McCONWAY & TORLEY COMPANY, OF PITTSBURGH, PENNSYLVANIA, A CORPORATION OF PENNSYLVANIA.

RAILWAY DRAFT APPLIANCE.

Application filed September 12, 1923. Serial No. 662,265.

To all whom it may concern:

Be it known that we, WILLIAM J. REGAN and ENOCH GEORGE, Jr., citizens of the United States, residing, respectively, at

5 Wilkinsburg, in the county of Allegheny and State of Pennsylvania, and Pittsburgh, in the county of Allegheny, State of Pennsylvania, have invented certain new and useful Improvements in Railway Draft Appliances; and we do hereby declare the following to be a full, clear, and exact description of the invention, such as will enable others skilled in the art to which it appertains to make and use the same.

10 Our invention relates to railway draft appliances and particularly to bushings forming liners for the slots with which car couplers and yokes are commonly provided for the reception of a connecting key. By 20 the use of the bushings, which may be made of such thickness as circumstances may require, a single coupler casting may be employed with any of the several sizes of keys now used.

15 The principal object of the invention is to provide a bushing of the character indicated which is of simple form, easily applied, readily removable so that when worn it may be replaced by a new one, and is securely 30 maintained in assembled relation to the draft member with which it is associated.

The principal feature of the invention, generally stated, consists in providing a draft member, having a key receiving slot 35 therein, with a bushing which extends into the slot, the said bushing being furnished with means cooperating with the draft member for maintaining said bushing in assembled position and being adapted to be deformed by bending so as to cause it to 40 assume assembled relation to the draft member.

A further feature of the invention consists in the combination with a draft member having a key receiving slot, of a bushing mounted on said draft member and extending into the slot thereof, the bushing being formed with a projection, the draft member being provided with a series of recesses for 45 alternately receiving the said projection so as to maintain the bushing in a plurality of assembled relations to the draft member, and the bushing being adapted to be bent

so as to cause it to assume an assembled position with respect to said draft member. 55

Another feature of the invention consists in mounting upon the draft member, having a key receiving slot therein, a split bushing which extends into said slot and is provided with a plurality of spaced projections 60 adapted to enter corresponding recesses formed in the draft member, there being a plurality of said recesses adapted to receive each of the projections and the bushing being formed of metal which may be 65 bent to cause the said projections to assume an assembled position in said recesses.

Other features of the invention pertaining to particular relations of parts and structural details will hereinafter appear. 70

In the drawings chosen for the purpose of illustrating the invention, the scope whereof is pointed out in the claims.

Figure 1 is a horizontal sectional view of a portion of a railway draft mechanism 75 embodying the invention.

Figure 2 is a side elevation of the rear end of the car coupler forming a part of the draft appliance illustrated in Fig. 1, the key slot bushing being shown as applied 80 to said coupler.

Figure 3 is a side elevation of the forward end of the draft yoke forming one of the elements of the draft rigging illustrated in Fig. 1, the key slot bushing being shown in 85 assembled relation thereto,

Figure 4 is a detail elevational view of one of the bushings illustrated in Fig. 1, the bushing being shown as bent so as to be entered in a key receiving slot of a draft member. 90

Figure 5 is a plan view of one of the bushings illustrated in Fig. 1.

Figure 6 is a detail view in side elevation of the rear end of a modified form of car 95 coupler for cooperating with the bushing.

Figure 7 is a plan view of the construction illustrated in Fig. 6.

The railway draft rigging illustrated in Fig. 1 is of the well known type involving 100 key connected draft members, one of which is the car coupler 1 while the other may be the usual draft yoke 2. The key 3, which is well known and is indicated in dotted lines in Fig. 1, passes through slots in the 105 car coupler and the arms of the yoke. As

the rear end of the coupler stem is commonly cast hollow the slot therein for receiving the connecting key 3 is frequently formed as two alined slots 4, and each yoke arm is 5 likewise provided with a slot 5. These slots are of somewhat greater size than the key 3 so as to afford space for the bushings which enter the slots and engage the said key.

10 The bushings 6 which extend into the respective slots 4 of the coupler may advantageously be formed as unitary members and preferably cover the entire inner surface of the slots. They are adapted to be 15 deformed by bending so as to permit them to be assembled with and disassembled from the draft member upon which they are mounted, and they are preferably either forged or made of malleable iron.

20 Each of the bushings 6 is provided with means for cooperating with the draft member to maintain said bushing in proper assembled position when the draft appliance is in service. For this purpose the bushing 25 may advantageously be provided with a plurality of spaced lugs or projections 7, one of which is adapted to enter either of the corresponding recesses 8 with which the coupler is furnished on its outer side adjacent the key slot, while the other of said lugs 7 is adapted to have overlapping engagement with the coupler within the hollow interior thereof. For economy of manufacture it is preferred in the case of the 30 car coupler to utilize the hollow interior of the coupler stem 1 as the recesses for receiving the inner lugs or projections 7 of the bushings, as recesses on the interior of the coupler corresponding in form to said 35 projections 7 would be somewhat difficult to clean out after the coupler is cast. The bushing 6, which is rounded at its ends to conform to the curvature of the slot, is preferably split near one end closely adjacent 40 to the projections 7, as indicated at 9, thus facilitating, as shown in dotted lines in Fig. 2, the bending of the bushing to permit its entry into the key slot and also enabling the subsequent bending necessary 45 to bring the projections 7 into cooperative relation with the draft member to be easily accomplished. To permit the projections 7 to enter and fit snugly in the recesses 8, the said projections are preferably tapered, as indicated at 10, and the recesses 8 are likewise tapered correspondingly, as indicated at 11.

Except that they are of less width in the direction of length, the bushings 12 for 60 the slotted arms of the draft yoke 2 are identical in form with those heretofore described, and accordingly similar reference characters have been applied to the corresponding details of construction. Each of 65 the yoke arms is preferably provided on its

inner and outer faces adjacent the key slots 5 with a plurality of recesses 8 either of which is adapted to receive the corresponding projections 7 of the bushing.

The form of bushing 6 illustrated in Figs. 70 6 and 7 is identical with that heretofore described. The coupler 13 is, however, provided on its outer sides with an increased number of recesses 14 for alternatively receiving the lugs or projections 7 of the 75 bushing.

It will be perceived that in all the forms of construction illustrated the bushing is capable of occupying a plurality of assembled positions with respect to the draft member upon which it is mounted, thus enabling said bushing, after it has been worn, to be taken out and reapplied so as to present new surfaces to the wearing action of the key. But it will be appreciated that 80 certain novel features of the invention are independent of the capability of assembling the bushings in various relations to the draft members with which they are associated.

We claim:—

1. In a railway draft appliance, the combination with a draft member having a key receiving slot therein, of a bushing mounted on said draft member and extending into said slot, said bushing being split and adapted to be bent so as to be entered in said slot, and being provided with means co-operating with said draft member to maintain said bushing in assembled position, said means being adapted to be moved from assembled position by a bending of the bushing.

2. In a railway draft appliance, the combination with a draft member having a key receiving slot therein, of a split bushing mounted on said draft member and extending into said slot, said bushing being adapted to be deformed by bending so as to cause it to be maintained in assembled relation to 100 said draft member.

3. In a railway draft appliance, the combination with a draft member having a key receiving slot therein, of a bushing mounted on said draft member and extending into said slot, said bushing being provided with a plurality of spaced lugs adapted to engage opposite sides of said draft member and being adapted to be bent so as to cause said lugs to assume a position for maintaining said bushing in assembled relation.

4. In a railway draft appliance, the combination with a draft member having a key receiving slot therein, of a bushing mounted on said draft member and extending into said slot, said bushing being split and provided with a plurality of spaced lugs adapted to engage said draft member to maintain said bushing in assembled position, and said bushing being adapted to be bent to cause 120

said lugs to assume their assembled positions.

5. In a railway draft appliance, the combination with a draft member having a key receiving slot therein, of a bushing mounted on said draft member and extending into said slot, said bushing being provided with a projection, said draft member being formed with a recess for receiving said projection when the bushing is in assembled position, and said bushing being adapted to be bent so as to cause said projection to enter said recess.

6. In a railway draft appliance, the combination with a draft member formed with a key receiving slot, of a bushing mounted on said draft member and extending into said slot, said bushing being provided with a projection, said draft member being formed with a plurality of recesses alternately adapted to receive said projection, and said bushing being adapted to be bent so as to cause said projection to be entered in said recesses or to be withdrawn therefrom.

7. In a railway draft appliance, the combination with a draft member having a key receiving slot therein, of a bushing mounted on said draft member and extending into said slot, said bushing being provided with a plurality of spaced projections, said draft member being formed with a plurality of spaced recesses, there being a plurality of said recesses for each of said projections, and said bushing being adapted to be bent to cause said projections to be entered in the corresponding recesses alternatively or be withdrawn therefrom.

8. In a railway draft appliance, the combination with a draft member having a key receiving slot therein, of a bushing mounted on said draft member and extending into said slot, said bushing being split and provided with a tapered projection, said draft member being formed with a tapered recess for receiving said projection when the bushing is in assembled position, and said bushing being adapted to be bent so as to cause said projection to enter said recess.

9. In a railway draft appliance, the combination with a draft member formed with a key receiving slot, of a bushing mounted on said draft member and extending into said slot, said bushing being provided with a projection and being split closely adjacent the latter, said draft member being formed with a recess for receiving said projection, and said bushing being adapted to be bent so as to cause said projection to enter said recess in assembled relation to said draft member.

10. In a railway draft appliance, the combination with a car coupler, of a yoke, said coupler and yoke having slots for receiving

a connecting key, of a bushing mounted on said car coupler and extending into the key receiving slot thereof, and a bushing mounted upon said yoke and extending into the key receiving slot of the latter, said bushing mounted upon the coupler being provided with means for preventing it from moving away from the adjacent side of the bushing which is mounted upon the yoke, and the bushing of said yoke being provided with means for preventing it from moving away from the adjacent side of the said bushing of the coupler.

11. In a railway draft appliance, the combination with a car coupler, of a yoke, said coupler and yoke having slots for receiving a connecting key, and bushings respectively mounted on said coupler and yoke and extending into the respective slots thereof, said bushings being adapted to be assembled in a plurality of alternative relations with respect to the member on which each is mounted.

12. In a railway draft appliance, the combination with a car coupler, of a yoke, said coupler and yoke having slots for receiving a connecting key, a bushing mounted upon said coupler and extending into the slot thereof, and a bushing mounted upon said yoke and extending into the slot of the latter, each of said bushings being split and adapted to be bent so as to be assembled in the slot of the member on which it is mounted, each of said bushings being provided with a plurality of spaced projections adapted to overlap portions of the respective members on which said bushings are mounted, and said projections being adapted to be caused to assume assembled position by bending the respective bushings.

13. In a railway draft appliance, the combination with a car coupler, of a yoke, said coupler and yoke having slots for receiving a connecting key, a bushing mounted on said coupler and extending into the slot thereof, and a bushing mounted on said yoke and extending into the slot thereof, said coupler being provided on its face adjacent said yoke with a recess adapted to receive a projection formed on the bushing carried by said coupler, and said yoke being provided on its face adjacent said coupler with a recess adapted to receive a projection formed on the bushing carried by said yoke.

14. A bushing for the key slot of a railway draft appliance member, said bushing being adapted to be bent and having projecting means for engaging the draft member upon which it is mounted.

In testimony whereof we affix our signatures.

WILLIAM J. REGAN.
